PHILIP J. STUHLTRAGER, OF PHILADELPHIA, PENNSYLVANIA.

Letters Patent No. 82,658, dated September 29, 1868.

IMPROVEMENT IN COMPOUND SAFE-DOOR HINGE.

The Schedule referred to in these Letters Patent and making part of the same.

TO ALL WHOM IT MAY CONCERN:

Be it known that I, PHILIP J. STUHLTRAGER, of Philadelphia, Pennsylvania, have invented a Compound Hinge for Safe-Doors, &c.; and I do hereby declare the following to be a full, clear, and exact description of the same.

My invention consists of a compound hinge, constructed and applied in the peculiar manner fully described hereafter, for the purpose of avoiding the necessity of rounding off or bevelling the outer edges of safe and other doors.

In order to enable others skilled in the art to make and apply my invention, I will now proceed to describe its construction and operation, reference being had to the accompanying drawing, which forms a part of this specification, and in which—

Figure 1 is an exterior view of my improved hinge applied to a safe-door.

Figure 2, a sectional plan view on the line 1-2, fig. 1.

Figure 3, the same, showing the door partly opened.

Figure 4, a perspective view, and

Figure 5 a rear view of the hinge as it appears when the door is partly opened.

Similar letters refer to similar parts throughout the several views.

A represents an ordinary fire or burglar-proof safe, and B the door of the same. The plates C C C of the hinge are secured to the front of the safe, and each plate is provided with a tubular projection, a, between which fit the tubular projections b b of a plate, D, the joint being completed by a rod, e, which is riveted at each end, or otherwise secured in its place, (see fig. 3.)

At the opposite side of the plate D are other tubular projections, b', between which are recesses for the reception of the projections, f, of a plate, E, the latter and the plate D being connected by a rod, g.

The third joint of the hinge is formed by tubular projections, f', of the plate E, and the projections h of two plates F F, which are secured to the door of the safe, the joint being completed, as in the former instances, by a single rod, i.

When a safe-door is hung upon ordinary single-jointed hinges, its outer edge, in order to open and close properly, and yet preserve a tight joint, must be bevelled or rounded off on the arc of a circle described from the centre of the hinge, as indicated by the dotted line x in fig. 2.

This bevelling of the outer edge necessitates a corresponding bevel or increase in the thickness of that portion of the safe with which the outer edge of the door has to coincide when closed. The bolts of the lock on the inside of the outer edge must also be thrown back towards the hinge, and their resistance to outward strain is consequently much decreased, while the edge of the door itself can be more readily cut away from the outside than if it were straight.

By the use of my compound hinge, however, the operation of which I will now proceed to describe, I am enabled to construct a door of any desirable thickness, and having a straight outer edge at right angles to the face of the door.

In fig. 2, the door of the safe is represented as closed and secured by a lock, H, worked, in the present instance, from the centre of the door, and having four bolts, i i i i, as shown in fig. 4.

After unlocking the door, it is not turned directly upon its hinge in the usual manner, as such motion would be prevented by the straight edges, y y, of the safe, but it is first drawn directly outwards until the door and the various sections of its hinge assume the position shown in fig. 3. The door may then be turned, as upon an ordinary hinge, to the position shown in fig. 4, or it may be opened to a still greater extent.

In closing the door, the operation is merely reversed, the door being first turned until opposite the opening in the front of the safe, and then pushed directly inward, the sections of the hinge adapting themselves to the various motions which are given to the door.

I prefer, for the sake of strength, to hang the door by one continuous hinge, as above described, but it will

be evident that two or more separate hinges may be used, and, if desired, portions of the hinge may be concealed, by moulding or otherwise, so as to expose but a small part of the same.

Although I have described my invention as applied to safe-doors only, it will be evident that it may be used in other instances, and, for some purposes, a hinge having more than three joints may be advantageously employed.

I claim as my invention, and desire to secure by Letters Patent—

A compound hinge, constructed and applied substantially as and for the purpose herein described.

In testimony whereof, I have signed my name to this specification in the presence of two subscribing witnesses.

PHILIP J. STUHLTRAGER.
